REFRIGERATION

George C. Pearce, Dayton, Ohio, assignor, by
mesne assignments, to General Motors Cor-
poration, a corporation of Delaware

Application September 29, 1932, Serial No. 635,391

21 Claims. (Cl. 62—4)

This invention relates to refrigeration, and more particularly to refrigerating systems of the character which operate continuously without stopping for temperature adjustments in an object being cooled. Such systems are stopped a relatively few times compared with the stopping operations of the usual intermittently operating refrigerating system which stops for temperature adjustments in the object being cooled. In the continuously operating systems or in those systems which are designed to operate substantially continuously and stop only for defrosting, repairs or the like, or when the atmospheric temperature drops below the normal range, the period of idleness is extremely long, so that the refrigerant pressure in the system will become substantially equalized throughout the system. Because of this, these systems need not, and generally are not, provided with special unloaders for the compressor, and therefore are likely to fail to restart if an attempt is made to restart them relatively soon after they have been stopped. It may occur, in the operation of these systems, that the line current, or source of electrical energy, may fail for a relatively short period of time, due to an electrical storm or the like, and it is desirable that the refrigerating system should restart automatically and safely after such a temporary failure of the line current.

It is among the objects of this invention to provide a control for the electric motor which drives the refrigerating system which is capable of automatically starting the motor when the current is turned on by the user, and which is capable of restarting the system safely if the line current, or source of electrical energy should be turned off temporarily and then be turned on before the refrigerant pressure has equalized sufficiently to permit the motor to start.

Further objects and advantages of the present invention will be apparent from the following description, reference being had to the accompanying drawing, wherein a preferred form of the present invention is clearly shown.

In the drawing:

Fig. 1 is a diagrammatic representation of a system embodying the features of my invention; and

Fig. 2 is a diagrammatic representation of a slightly modified system.

A refrigerating system embodying features of this invention is designed to operate continuously during the normal atmospheric temperature range maintained in a dwelling without stopping for cabinet temperature adjustments, and is of

such a character and capacity, that it automatically maintains proper temperature conditions in the object to be cooled, notwithstanding such continuous operation. Such a system has been more fully described in the copending application, Serial No. 599,239, filed March 16, 1932, to which reference is hereby made for a further disclosure of such a system.

Briefly, such a system includes a compressor 10, a condenser 11, an evaporator 12. The compressor discharges the compressed refrigerant to the condenser 11 which in turn discharges liquefied refrigerant through the expansion device 13 to the evaporator 12 where the refrigerant is evaporated and returns through the line 14 to the compressor 10. The expansion device 13 may be of any suitable character, but preferably is of the elongated orifice type which maintains a fixed, and continuously open orifice, so calibrated as to length and cross-sectional area, that it maintains the evaporator 12 at the proper temperature to maintain the object being cooled at a substantially constant temperature notwithstanding variations in the surrounding atmosphere. In such a system, the elongated orifice in the expander 13 permits a continuous passage of refrigerant therethrough, and should the compressor 10 stop temporarily, this flow through the orifice continues and in a relatively short time equalizes the pressures throughout the refrigerating system, so that if the compressor should be restarted after such a short time, it starts with substantially no load.

Under ordinary conditions, such a system is stopped only for the purpose of defrosting the evaporator 12 and this defrosting operation is performed only once or twice a month and is not of the type of stopping operation which is intended to maintain temperature conditions in the object being cooled. On the contrary, such a stopping operation generally permits the object being cooled to warm above the desired temperature, but the operation is performed because of the large accumulation of frost on the evaporator and because of its undesirable inconvenience. After such a stopping operation and because of its long duration, the compressor starts under no load characteristics and hence the compressor need not be provided with unloading mechanism, other than the expander 13 itself. The motor 15 for driving the compressor may be of the split phase type which is provided with a starting winding 16 and a running winding 17, and, as is usual with this type of motor, the starting torque is small. Such a motor compressor unit

is capable of starting only if the entire refrigeration system has become substantially equalized as to pressure throughout, or if the unit is provided with an automatic unloader for removing the pressure differential load during the starting period. In this particular system, no unloader need be used, as it is possible to permit the system to equalize during the infrequent stops which may be necessary.

10 The starting control for such a system includes a device or relay 18 for maintaining a flow of current from the source of electrical supply A through the starting winding during the starting period and for stopping the flow of said current at the termination of the starting period. The control also includes devices for rendering the means or relay 18 safely reoperative after a temporary failure of the source of electrical energy and for preventing too frequent a starting and stopping of the motor after such failure of such source of electrical energy if the compressor should fail to permit the motor to start. To this end the relay 18 may include a solenoid 19 in series with the running winding 17 which 15 actuates the contact 20 for energizing the starting winding 16. The construction is such that the surge current running through the running winding during the starting period is sufficient to pull the contact 20 against gravitational forces, 20 or against a magnetic force, during the starting period of the motor so that the starting winding 16 is energized during such period; but the solenoid 19 is not of sufficient strength to hold the contact 20 in closed position after the current through the winding 17 drops to the normal running value at the termination of the starting period.

An overload relay 21 is provided which prevents the surge current from running through the motor for too long a period of time if the motor should fail to start. Thus means are provided for opening the electrical circuit if the motor fails to start after a predetermined period. To this end an overload relay 21 is provided in the form of a resistance 22 which heats the thermostatic strip 23 to open the contact 24 with a snap action against a resistance such as the permanent magnet 25. Thus if the motor should fail to start after a predetermined period, the resistance 22 becomes heated and causes the thermostatic strip 23 to maintain the circuit open until the resistance 22 and the thermostatic strip 23 become cooled. This control may be so constructed that the heating and cooling period may be of any desired length, for example, two minutes each, so that if the motor fails to start for two minutes after it has been re-energized, the circuit will remain open for two minutes while the control 21 is cooling. During these four minutes involving the heating and cooling of the relay 21, the refrigerant continuously flows through the expander 13, and reduces the refrigerant pressure differential in the compressor, so that the compressor offers less starting resistance to the motor 15 after the expiration of such four minutes, when the circuit is again closed, and the motor once again attempts to start. If unsuccessful again, the control 21 heats again and thus permits another four minute period to lapse before the third attempt is made to restart the motor.

It sometimes occurs that in the repeated starting attempts above described, the motor becomes overheated and it is therefore desirable to provide a long period of rest to permit the motor to cool and to insure that the refrigerating sys-

tem has become thoroughly equalized before again attempting to start the motor. To this end another control 26 is provided. This control requires a longer period of time before it becomes operative than is required by the control 21 and also maintains the circuit open for a longer period after such failure to start than the period maintained by the control 21. Thus the control 21 may cycle several times before the control 26 becomes operative. This may be accomplished by mounting the thermostatic strip 27 on the motor casing 28. This strip 27 actuates the contact 29 against a resistance such as the permanent magnet 30 to open the circuit with a snap action after the strip 27 has been heated to a predetermined temperature. The length of time required to heat the strip 27 to this temperature is much longer than that required to heat the strip 23, because the casing 28 contains more metal than is contained in the resistance 22 and therefore heats or cools much more slowly. The strip 27 is adapted to close the contact 29 after the casing 28 has cooled to a predetermined temperature, and this cooling period is much greater in length than the cooling period of the resistance 22. Thus if the motor 15 fails to start after several attempts have been initiated by the control 21, the control 26 opens the circuit and maintains it open for a major period of time which is much longer than the minor periods of rest maintained by the control 21.

A manual control for stopping and starting the system by the user for defrosting, or the like, may be provided. Conveniently one of the contacts already provided may be used. Thus a stop 31 may be provided on the rod 32, which rod may be slidably connected with strip 23 in such a manner that the contact 24 may be opened without disturbing the strip 23. A snap acting, manually operated, lever construction 33 is provided to engage the hook 34 which forms an extension of the rod 32. Thus the user may operate the lever construction 33 to open the contact 24 or may operate it to permit the contact 24 to be governed by the control 21.

In the modification shown in Fig. 2, means are provided which require a manual reset if the motor fails to start after a repeated number of starting attempts after a temporary line failure. To this end the control 26 of Fig. 1 is replaced by a manual reset control 40 shown in Fig. 2. The remaining portion of the system, having numerals similar to this Fig. 1, but with the suffix "a" attached, may be the same as the system shown in Fig. 1. The manual reset control 40 may include a spring member 41 tending to open the contact 42 which, in turn, opens the electric circuit leading to the motor 15a. The spring 41 is prevented from opening the contact 42 by means of a hook 43 which is in engagement with the ratchet wheel 44. The ratchet wheel 44 is soldered to the stationary shaft 45 mounted on the motor casing 28a by means of low melting point solder. After repeated attempts to start the motor by means of the automatic control 21a, the motor casing 28a becomes overheated and melts the solder which holds the ratchet wheel 44 stationary on the shaft 45. When the solder is melted, the ratchet wheel turns and permits the spring 41 to open the contact 42, and thus opens the circuit to the motor 15a. The circuit remains open, until the button 46 is manually operated to close the contact 42 and to engage the hook 43 in the ratchet 44 after the casing 28a has cooled sufficiently to permit the solder to 75

solidify and again prevent the ratchet 44 from turning.

While the form of embodiment of the invention as herein disclosed, constitutes a preferred form, it is to be understood that other forms might be adopted, all coming within the scope of the claims which follow.

What is claimed is as follows:

1. A refrigerating system including a compressor, condenser and evaporator in a closed refrigerant cycle, an electric motor for driving said compressor, said motor having a starting winding and a running winding, a source of electrical energy, a starting control switch for maintaining the flow of current from said source through said starting winding during a starting period and for stopping the flow of said current at the termination of said starting period, means for rendering said starting control switch temporarily inoperative after failure of said electric motor to restart after a temporary failure of said source of electrical energy, and a continuously open expansion device between said condenser and evaporator.

2. A refrigerating system including a compressor, condenser and evaporator in a closed refrigerant cycle, an electric motor for driving said compressor, said motor having a starting winding and a running winding, a source of electrical energy, a starting control switch for maintaining the flow of current from said source through said starting winding during a starting period and for stopping the flow of said current at the termination of said starting period, means for rendering said starting control switch temporarily inoperative after failure of said electric motor to restart after a temporary failure of said source of electrical energy, a continuously open expansion device between said condenser and evaporator, and means responsive to temperature of said motor for rendering said starting control switch inoperative while said motor is over-heated.

3. Refrigerating apparatus including a compressor, condenser, and evaporator connected in a closed circuit, said closed circuit having a continuously open restricted connection between the condenser and evaporator for controlling the flow of refrigerant to the evaporator during the operation of the compressor, and for equalizing pressures within the system to unload the compressor when the compressor is idle, an electric motor having a starting circuit and a running circuit for driving the compressor, means for connecting the starting circuit to a source of electric energy, and means for opening the motor circuit and for preventing the energization of said first mentioned means when the pressures in the closed refrigerant circuit have not equalized sufficiently to permit starting of the electric motor, said opening means including means for reclosing the motor circuit after a period of rest.

4. Refrigerating apparatus including a compressor, condenser, and evaporator connected in a closed circuit, said closed circuit having a continuously open restricted connection between the condenser and evaporator for controlling the flow of refrigerant to the evaporator during the operation of the compressor, and for equalizing pressures within the system to unload the compressor when the compressor is idle, an electric motor having a starting circuit and a running circuit for driving the compressor, means for connecting the starting circuit to a source of electric energy, and means for opening the motor circuit when said first mentioned means is ineffective to start the electric motor, said opening means after a

period of rest being effective to reclose the motor circuit.

5. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, means adapted to open the first circuit controller when the motor approaches running speed after starting, and means for opening the second circuit controller upon the flow of excessive current and for automatically closing the second circuit controller after an interruption of the flow of current to the running winding.

6. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling both windings, means adapted to open the first circuit controller when the motor approaches running speed after starting, and means for opening the second circuit controller upon the flow of excessive current and for automatically closing the second circuit controller after an interruption of the flow of current to the running winding.

7. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, means adapted to open the first circuit controller when the motor approaches running speed after starting, and means for opening the second circuit controller upon the flow of excessive current and for automatically closing the second circuit controller after an interruption of the flow of current to the running winding, said last named means including time delay means for preventing maintenance of the second circuit controller in closed position until a predetermined time has elapsed after the occurrence of an excessive current flow in the motor.

8. In a refrigerating apparatus, the combination of a compressor, a condenser, a constantly open liquid refrigerant control device, and an evaporator in a closed refrigerant circuit, an electric motor for driving said compressor having a starting torque insufficient to start the compressor against pressure differences of the order existing thereacross during normal operation of the apparatus, said motor having a starting winding and a running winding, a first circuit

controller for controlling the starting winding, a second circuit controller for controlling both windings, means adapted to open the first circuit controller when the motor approaches running speed after starting, and means for opening the second circuit controller upon the flow of excessive current and for automatically closing the second circuit controller after an interruption of the flow of current to the running winding, said last named means including time delay means for preventing maintenance of the second circuit controller in closed position until a predetermined time has elapsed after the occurrence of an excessive current flow in the motor.

15. 9. In a refrigerating apparatus, the combination of a compressor, a condenser, a constantly open liquid refrigerant control device, and an evaporator in a closed refrigerant circuit, said compressor being constantly exposed to the pressures existing in the evaporator and condenser, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, means adapted to open the first circuit controller when the motor approaches running speed after starting, and means for opening the second circuit controller upon the flow of excessive current and for automatically closing the second circuit controller after an interruption of the flow of current to the running winding.

10. In a refrigerating apparatus, the combination of a compressor, a condenser, a constantly open liquid refrigerant control device, and an evaporator in a closed refrigerant circuit, said compressor being constantly exposed to the pressures existing in the evaporator and condenser, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, means adapted to open the first circuit controller when the motor approaches running speed after starting, and means for opening the second circuit controller upon the flow of excessive current and for automatically closing the second circuit controller after an interruption of the flow of current to the running winding, said last named means including time delay means for preventing maintenance of the second circuit controller in closed position until a predetermined time has elapsed after the occurrence of an excessive current flow in the motor.

11. In a refrigerating apparatus, the combination of a compressor, a condenser, a constantly open liquid refrigerant control device, and an evaporator in a closed refrigerant circuit, said compressor being constantly exposed to the pressures existing in the evaporator and condenser, an electric motor for driving said compressor having a starting torque insufficient to start the compressor against pressure differences of the order existing thereacross during normal operation of the apparatus, said motor having a starting winding and a running winding, a first circuit controller for controlling the starting winding, a second circuit controller for controlling at least the running winding, means adapted to open the first circuit controller when the motor approaches running speed after starting, and means for opening the second circuit controller upon the flow of excessive current and for automatically closing the second circuit controller after an interruption of the flow of current to the running winding.

cuit controller for controlling the starting winding, a second circuit controller for controlling at least the running winding, means adapted to open the first circuit controller when the motor approaches running speed after starting, and means for opening the second circuit controller upon the flow of excessive current.

12. In a refrigerating apparatus, the combination of a compressor, a condenser, a constantly open liquid refrigerant control device, and an evaporator in a closed refrigerant circuit, said compressor being constantly exposed to the pressures existing in the evaporator and condenser, an electric motor for driving said compressor having a starting torque insufficient to start the compressor against pressure differences of the order existing thereacross during normal operation of the apparatus, said motor having a starting winding and a running winding, a hermetically sealed casing enclosing the motor and compressor, a first circuit controller for controlling the starting winding, a second circuit controller for controlling at least the running winding, means adapted to open the first circuit controller when the motor approaches running speed after starting, and means for opening the second circuit controller upon the flow of excessive current.

13. In a refrigerating apparatus, the combination of a compressor, a condenser, a constantly open liquid refrigerant control device, and an evaporator in a closed refrigerant circuit, said compressor being constantly exposed to the pressures existing in the evaporator and condenser, an electric motor for driving said compressor having a starting torque insufficient to start the compressor against pressure differences of the order existing thereacross during normal operation of the apparatus, and means for interrupting the flow of current to the motor after current flow is initiated at a time when the pressure difference between the condenser and the evaporator is too great to permit the motor to start.

14. Refrigerating apparatus including a closed refrigerant system comprising a compressor, condenser, and evaporator, an electric motor having a starting circuit and a running circuit for driving the compressor to circulate refrigerant and to create a pressure difference in the system on either side of the compressor, said system being provided with means for reducing the pressure differential across the compressor when the compressor is idle to unload the compressor, means for connecting the starting circuit to a source of electric energy to start the compressor, and means for opening the motor circuit for preventing the energization of the electric motor when the pressure differential across the compressor has not been reduced sufficiently to permit starting of the electric motor, said opening means including means for reclosing the motor circuit after a period of rest.

15. Refrigerating apparatus including a closed refrigerant system comprising a compressor, condenser, and evaporator, an electric motor having a starting circuit and a running circuit for driving the compressor to circulate refrigerant and to create a pressure difference in the system on either side of the compressor, said system being provided with means for reducing the pressure differential across the compressor when the compressor is idle to unload the compressor, means for connecting the starting circuit to a source of electric energy to start the compressor, and means responsive to the electric motor current and to electric motor temperature for preventing the

- energization of the electric motor under dangerous conditions.
16. Refrigerating apparatus including a closed refrigerant system comprising a compressor, condenser, and evaporator, an electric motor having a starting circuit and a running circuit for driving the compressor to circulate refrigerant and to create a pressure difference in the system on either side of the compressor, said system being provided with means for reducing the pressure differential across the compressor when the compressor is idle to unload the compressor, means for connecting the starting circuit to a source of electric energy to start the compressor, and means responsive to the electric motor current and to electric motor temperature for opening the electric motor circuit under dangerous conditions and thereafter closing the circuit automatically when the condition has improved.
17. A refrigerating system including a compressor, a condenser and an evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means for preventing the flow of current through said windings for a predetermined period of time if said temporary interruption should prove to be of insufficient duration to unload said refrigerating system, said period of time being longer than said starting period, and means for equalizing refrigerant pressures in said system during said predetermined period.
18. A refrigerating system including a compressor, a condenser and an evaporator in a closed refrigerant circuit, an electric motor for driving said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means for preventing the flow of current through said windings for a predetermined period of time if said temporary interruption should prove to be of insufficient duration to unload said refrigerating system, said period of time being longer than said starting period, and a continuously open expansion device between said condenser and evaporator for equalizing refrigerant pressures in said system during said predetermined period.
19. A refrigerating system including a compressor, a condenser and an evaporator in a closed refrigerant circuit, an electric motor for driving

said compressor, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means for preventing the flow of current through said windings for a predetermined period of time if said temporary interruption should prove to be of insufficient duration to unload said refrigerating system, and means for equalizing refrigerant pressures in said system during said predetermined period.

20. A refrigerating system including a compressor, a condenser and an evaporator in a closed refrigerant circuit, an electric motor for driving said compressor, a hermetically sealed casing enclosing said motor and compressor, said compressor being constantly subjected to the pressure difference between the condenser and the evaporator, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means for preventing the flow of current through said windings for a predetermined period of time if said temporary interruption should prove to be of insufficient duration to unload said refrigerating system, said period of time being longer than said starting period, and means for equalizing refrigerant pressures in said system during said predetermined period.

21. A refrigerating system including a compressor, a condenser and an evaporator in a closed refrigerant circuit, an electric motor for driving said compressor, a hermetically sealed casing enclosing said motor and compressor, said compressor being constantly subjected to the pressure difference between the condenser and the evaporator, said motor having a starting winding and a running winding, a source of electrical energy, means for maintaining the flow of current from said source through said starting winding during a starting period and for stopping the flow of said current at the termination of said starting period, means for rendering said first named means reoperative after a temporary interruption in the supply of electrical energy, means for preventing the flow of current through said windings for a predetermined period of time if said temporary interruption should prove to be of insufficient duration to unload said refrigerating system, and means for equalizing refrigerant pressures in said system during said predetermined period.

GEORGE C. PEARCE.
